UNITED STATES PATENT OFFICE.

JOSEPH LEONARD, OF ALLENTOWN, PENNSYLVANIA, ASSIGNOR TO CHARIS CORPORATION, OF ALLENTOWN, PENNSYLVANIA, A CORPORATION OF NEW YORK.

SUPPORTING STRAP FOR GARMENTS.

Application filed June 18, 1927. Serial No. 199,804.

This invention relates to an improvement in shoulder or supporting straps for women's garments, and more particularly to the connecting means between the shoulder strap and the garments, one of the principal objects of the invention being the provision of a connecting means which, while being invisible while attached, will at the same time be susceptible of ready and easy attachment and detachment.

Another object of the invention is to provide cooperating connecting means between the garment and strap having advantages of construction, method of manufacture and assembly, and advantages of use, which result in an economical, simple, yet strong and convenient device.

A further object is to provide a connecting means between the garment and shoulder strap in which the portion of the fastener attached to the garment operates to distribute the tension due to the pull on the strap when the garment is in use, over a considerable area of the garment, and in which the portion of the fastener attached to the strap likewise will distribute the pull over the entire width of the strap with the resultant advantages that button-pull is avoided, the strap is maintained in flat condition, and the garment is relatively uniformly supported without the disadvantages of localized strains or pulls.

A further object is to provide a device having in addition to the advantages just pointed out, that of adjusting itself to the shape of the shoulder and allowing ready change of angular relation between the strap and garment, to afford conformity to the movements of the wearer without slipping and without undue strain upon or disarrangement of the strap or garment.

In the drawings, which are illustrative of one embodiment of the invention,—

Figure 1 is a view in perspective of the upper portion of a garment and the supporting straps thereof with the invention applied thereto.

Figure 2 is an enlarged fragmentary view of a portion of Figure 1.

Figure 3 is a fragmentary vertical sectional view through the portion of the garment having the invention applied thereto, the pocket being shown in extended or opened position for convenience of illustration.

Figure 4 is a fragmentary view in elevation from the inside of the garment.

Referring more particularly to the drawing, a garment is indicated at A, and the supporting straps at B. The former, at the points where the ends of the supporting straps are to be attached, is provided with pockets, similarly formed. Each of the pockets is made by sewing, as at 5, to the rear side of the garment, adjacent its upper edge, a doubled piece of cloth 6, preferably of the same material of which the garment is made. The pocket is to receive and hide from view the portion of the connecting means which is carried by the strap, and the doubled cloth or patch 6 is to support the garment member of the connecting means and to distribute the pull or tension exerted by the strap over a considerable area of the garment.

The portion of the connecting means carried by the garment comprises a metal plate 7, having a headed stud 8 thereon. The plate is positioned in a channel 9, between the folds of the cloth or patch 6, such channel being formed by parallel rows of stitches 10 extending the length of the patch 6 and parallel with the folded edge 11 thereof. In forming the connecting means, before the cloth 6 is sewed to the garment, the plate 7 is slipped into the channel formed by the spaced rows of stitching, and moved therein to the desired position, and the cloth over the head of the stud is then pierced or cut to allow the head to project through. Or, if desired, the plate may be positioned when the cloth is first folded, an incision being made to accommodate the stud head, and the rows of stitches may then be run with the plate in place, the cloth or patch thereafter being sewed in the proper position to the garment. In either method of assembly the plate is held in position, and the stud retained against pulling the cloth by the rows of stitching 10, and such stitches serve the further purpose of transmitting the pull embodied by the strap more directly to the portions of the garment adjacent the ends of the cloth 6 than would be the case were this pull transmitted by the cloth alone, since there would be a tendency in the latter case, for a much greater proportion of the pull being transmitted directly downwardly than laterally.

The portion of the connecting means car-

ried by the straps B in each case, includes a loop 12, the opposed bowed ends 13 of which are disposed between the folds of the doubled over end 14 of the strap, such folds being stitched together as at 21. The stud-engaging portion of the loop extends through an opening or incision 15 in the end fold 16 of the strap, and is bowed outwardly as at 17, to allow the loop to engage over the stud head. The extremity of the loop at 18, is of small diameter to receive the stud shank, and the loop is restricted between these portions as at 19, to provide a snap fastening which must be sprung apart to receive the shank, such snap fastening thereby holding the loop in engagement with the stud until forcibly detached. It is to be noted that the folds at the end of the strap are stitched together at 20, along the line immediately above and in close proximity to the opposed bowed ends of the loop, thereby forming a channel of a width to snugly accommodate the loop and co-extensive in length with the width of the strap.

25 The loop is likewise substantially co-extensive with the width of the strap to thereby distribute the pull or tension entirely across the strap, such distribution being materially aided by the fact that the row of stitches 20 lies closely along the upper edge of the loop. Thus button pull or uneven distribution on the tension of the strap is prevented.

30 The loop may swing about the stud as a pivot, to thereby allow ready change of angular relation between the strap and the garment, thus affording conformity to the movements of the wearer without undue strain upon, or disarrangement of the strap or garment.

40 As indicated in Figure 1, the garment and strap may be equipped with the attaching means according to this invention, for both ends of each strap, so that the straps may be entirely disconnected as for laundering purposes or exchange of straps so that those employed may conform to the color of the outer garments. It is obvious, of course, that if desired, the strap or straps at one end may be permanently affixed, instead, to 45 the garment.

50 It will be noted that the position of the plate 7 is such that when the strap is connected to the garment, the lower portion thereof extends slightly into the pocket, so that the fastening means which detachably connects the strap to the garment is entirely hidden from view, an extremely neat arrangement being thus provided.

55 The foregoing detailed description has been given for purposes of clearness of understanding, and no undue limitations should be deduced therefrom, but the appended claims should be construed as

broadly as permissible, in view of the prior art.

Having thus described my invention what I claim as new, and desire to secure by Letters Patent is:—

1. The combination with a garment, of a pocket formed by sewing a doubled patch thereto adjacent the upper edge thereof, a metallic plate arranged between the folds of the patch at a point substantially intermediate the depth of the pocket and having a headed stud extending through one wall 75 of the patch into the pocket, rows of stitches above and below the plate and in close proximity thereto and extending the length of the patch to aid in distributing laterally the pull on the stud, a supporting strap 80 doubled at its end and adapted when attached to the garment to extend into the pocket, a metallic loop having the opposed bowed end portions thereof positioned between the folds of the strap end and having 85 a stud-engaging portion extending through an opening in the end fold, and a row of stitches connecting the folds of the strap end together and located above and in close proximity to said loop.

2. The combination with a garment, of a pocket formed by sewing a doubled patch thereto, a metallic plate arranged between the folds of the patch and having a stud extending through one wall of the patch 90 into the pocket, means securing the plate in position in the patch and aiding in distributing laterally the pull on the stud, a supporting strap doubled over at its end, a metallic loop positioned between the folds 95 of the strap and having a stud-engaging portion extending through an opening in the end fold, and means retaining the loop 100 in position in the strap and aiding in distributing transversely of the strap, the pull thereon incident to strains set up by movements of the wearer when the stud and loop are engaged.

3. The combination with a garment, of a pocket formed by sewing a doubled patch 110 thereto, a channel formed between the walls of the patch between rows of stitches, a metallic plate located in such channel and having a stud extending into the pocket, a supporting strap adapted when connected with the garment to extend into the pocket, such strap having its end folded, and a metallic loop substantially the width of the strap positioned between the end folds 115 thereof and having a stud-engaging portion 120 extending through an opening in the end fold at the extremity of the strap and adapted to engage the stud.

In testimony whereof I hereunto affix my signature.

JOSEPH LEONARD.
